FREDERICK A. FELDKAMP, OF NEWARK, NEW JERSEY.

ELECTRIC CLOCK-WINDING MECHANISM.

Application filed January 19, 1927. Serial No. 162,067.

This invention relates to electric clock-winding mechanism; and the invention has reference, more particularly, to electric motor actuated spring winding mechanism adapted 5 for connection with ordinary lighting or power circuits, including a novel automatic circuit make and break means whereby the winding motor is periodically started and stopped to restore the expended energy of the 10 clock spring or equivalent clock-work driving means.

The invention has for its principal object to provide a very simple winding motor circuit control switch mechanism which, on the 15 one hand, is actuated by the clock-work driving operation of the clock-spring to periodically close the circuit to cause the spring winding mechanism to function, and, on the other hand, being actuated by the operation 20 of said spring winding mechanism to open the circuit upon completion of the winding operation; said control switch mechanism being of such character that should the service of electric power be interrupted for one 25 or more switch closing periods with resultant failure of winding function, the clock will continue to run until, upon restoration of electric power service at any time before the total expenditure of spring-power occurs a 30 subsequent closing of the switch will be automatically maintained long enough to permit the winding mechanism to restore the spring to fully wound condition.

Another object of this invention is to provide means to assure the maintenance of the control switch in closed condition in the event the clock-spring runs down completely, so that upon restoration of electric power service the winding mechanism will at once 40 automatically function to fully rewind the spring and thereby restart the operation of the clock.

Other objects of this invention, not at this time more particularly enumerated, will be 45 clearly understood from the following detailed description of the same.

In carrying out my present invention, I provide a single control switch means in the form of an arm pivoted to swing in both 50 vertical and horizontal planes, and carrying a bridging contact to cooperate with a pair of spaced stationary contact elements of op-

posite polarity which are connected in the electric circuit serving the spring winding motor. To control at proper times the circuit closing and opening movements of said switch arm, I provide an externally threaded shaft or spindle which is stationary while the clock-spring is unwinding, but which is so connected with the spring winding mechanism as to be rotated thereby during the spring winding operation. Cooperating with the threads of said shaft or spindle, so as to be longitudinally movable thereon, is a shift-gear which is in geared relation to the 65 spring actuated clock-work driving gear, whereby the same is rotated and caused to travel on the threaded shaft or spindle in a direction away from the switch-arm. Coupled with said shift-gear, so as to be rotated thereby, is a switch arm for movement into closed relation to said stationary circuit contacts. When the switch-arm is thus moved to circuit closing position, with consequent operation of the spring-winding motor, the 70 threaded shaft or spindle will at once be rotated, by the operation of the spring-winding mechanism, relative to the shift-gear, so that the latter is caused to travel toward the switch-arm while the spring is being wound, 75 and at the end of such travel will be caused to engage said switch-arm so as to swing the same to circuit interrupting relation to the stationary circuit contacts, thus stopping the 80 motor driven winding mechanism upon completion of the spring winding operation. The shift-gear is so sized relative to the 85 spring-actuated clock-work driving gear that the same makes a plurality of revolutions relative to one of the latter, and since the switch-arm trip-cam rotates with the shift-gear, it follows that the switch-arm will be periodically released several times for closing movement during the total unwinding capacity of the clock-spring. So long as the 90 service of current through the circuit feeding the winding motor is not interrupted at the time of switch closing, rewinding will take place at the completion of each rotation of the trip-cam. Should the circuit be dead at 95 the time of the first or any subsequent closing of the switch, the switch opening and closing operations will be repeated periodically while the clock-spring continues to unwind, until

such time as the switch closes a live circuit. In the meantime the shift-gear will travel on the threaded shaft or spindle farther and farther away from the switch-arm, so that 5 when rewinding does take place it will require more revolutions of the threaded shaft or spindle to move said shift-gear back to switch-arm engaging and opening position, and consequently the time or duration of 10 winding operation will be proportionally lengthened in every instance to that required to restore the spring to fully wound condition.

The invention is clearly illustrated in the 15 accompanying drawings, in which:

Figure 1 is a fragmentary side elevation of a portion of a spring actuated clock-work illustrating the rotation of the spring winding mechanism thereto, together with the 20 novel electric circuit control switch mechanism;

Figure 2 is a top plan view of the same, showing diagrammatically the electric circuit connections between the novel control switch 25 mechanism and the spring winding motor;

Figure 3 is a transverse vertical section, taken on line 3—3 in Figure 1;

Figure 4 is a fragmentary side elevation of the switch operating mechanism;

Figure 5 is a detail cross section, taken 30 on line 5—5 in Figure 3;

Figure 6 is a fragmentary side elevation showing the closed position of the switch means;

Figure 7 is a fragmentary top plan view, showing the operating mechanism as it functions to open the switch upon completion of a spring winding operation;

Figure 8 is a fragmentary side elevation 40 of the switch operating mechanism, showing the position of the same holding the switch means in closed position after the clock-spring has completely run down; and

Figure 9 is a transverse section, taken on 45 line 9—9 in said Figure 8.

Similar characters of reference are employed in all of the hereinabove described views, to indicate corresponding parts.

Referring now to said drawings, the reference characters 10 and 11 respectively indicate the spaced frame-plates of a suitable clock-work frame, in and between which is journaled the clock-spring arbor 12. The usual spirally wound clock-spring 13 is provided, the inner end of the same being secured to said arbor 12, and the outer end of the same being secured to the enclosing spring drum 14, arranged to rotate freely on said arbor 12. Fixed on said arbor 12 55 is the spring driven clock-work driving gear 15, which operates the usual clock gear train and escapement, not shown. Fixed in connected relation to said spring drum 14, so as to freely rotate therewith relative to the arbor 12, is the spring-winding gear 16.

The reference character 17 indicates any suitable form of electric motor (diagrammatically shown in Figure 2), and which is adapted to provide the power for winding the clock-spring 13. The armature shaft 18 70 of said motor is journaled at its outer end in a suitable bearing frame 19 connected with the clock-work frame, and secured on said armature shaft 18 is a worm gear 20 which meshes with and drives a worm-wheel 21, the 75 shaft 22 of which is suitably journaled in said clock-work frame and the bearing frame 19. Fixed on said worm-wheel shaft 22 is a reduction gear 23, which meshes with and drives the spring-winding gear 16. 80

Journaled in and between bearing expansions 24 and 25 of the respective frame-plates 10 and 11, so as to parallel the arbor 12, is the spindle 26 of a winding-motor circuit switch controlling mechanism, the same 85

having at one end thereof an externally screw-threaded section 27, preferably of somewhat enlarged diameter. Fixed on said spindle 26 is a pinion 28 which meshes with and is driven by the spring-winding gear 16. 90 The reference character 29 indicates a shift-gear, which is provided adjacent to its outer end with an internally screw-threaded internal hub-portion 30 to cooperate with the screw-threaded section 27 of the spindle 26. 95 Mounted on said spindle 26, so as to rotate freely thereon, is a trip-cam 31, the same being coupled with said shift-gear 29 so as to be rotated thereby, while nevertheless admitting of independent longitudinal shifting movement of said shift-gear relative said spindle and its threaded section. The means for so coupling said trip-cam and shift-gear comprises the provision in the inner end portion of the latter a chambered interior 100 whereby the same can telescopically slide upon the adjacent end portion of the former, said trip-cam having a longitudinal channel or key-way 32 in its external surface, with which is engaged an internal key 33 with which the shift-gear is provided, all as shown more especially in Figures 3 and 5 of the accompanying drawings. Said shift-gear 29 meshes with said spring-actuated 105 clock-work driving gear 15 so as to be rotated thereby at proper times. Said trip-cam 31 is provided, beyond said shift-gear 29, with a cam-nosing 34.

The frame-plate 10 is provided with a 110 suitably located bracket-portion 35. Mounted on said bracket-portion 35, so as to swivel on its vertical axis, is a fulcrum-post 36. Pivottally connected with the free end of 115 said fulcrum-post 36 so as to swing or move in vertical plane is a switch-arm 37, disposed to extend above and across said trip-cam 31. Said switch-arm 37 is provided on its under side with a trip-nosing 38 to cooperate with the cam-nosing 34 of said trip-cam 31.

Suitably located and supported by and so

as to extend between the frame-plates 10 and 11 is base-plate 39 of insulating material. Fixed to and supported by said base-plate 39 is one of a pair of stationary circuit contacts, comprising a foot-piece 40, having at one end a vertically disposed or upstanding contact arm 41. Also fixed to and supported by said base-plate 39 is the other of said pair of stationary circuit contacts, the same comprising a contact plate 42 horizontally disposed adjacent to but electrically separated from said upstanding contact arm 41. An electric current delivery circuit wire 43, leading from a suitable electrical source, is connected with the foot-piece 40 of the contact arm 41. Leading from the contact plate 42 to one pole of the spring winding motor 17 is a current delivery circuit wire 44. Leading from the opposite pole of the spring winding motor 17 back to the electrical source is a return circuit wire 45. Carried on the free end of said switch-arm 37, but preferably insulated therefrom by an intermediate body 46 of insulating material is a bridging contact member comprising a vertical portion 47 to engage with said upstanding contact arm 41 and a horizontal portion 48 to engage with said horizontal contact plate 42. The reference character 49 indicates a pull-spring diagonally interconnected between said switch-arm 37 and the frame-plate 11, whereby its tension serves to pull, at proper times, said switch-arm both sideways or horizontally to engage its bridging contact member with said horizontal contact plate 42.

Said shift-gear 29 is provided adjacent to its inner end, and disposed between a pair of properly located teeth thereof, with a stop-piece 50, the purpose of which will be hereinafter explained.

In operation, when the clock-spring 13 is fully wound the shift-gear 29 occupies its inwardly moved position on the threaded section 27 of the spindle 26, in which position it has moved the switch-arm 37 sideways to remove the portion 47 of its bridging contact means from engagement with the upstanding stationary circuit contact 41, while the portion 48 of said bridging contact means remains in engagement with the horizontal stationary circuit contact 42, the service of current to the winding motor 17 having thus been interrupted, and the spring winding mechanism stopped so that the spindle 26 and its threaded section 27 remains stationary (see Figure 7). As the clock-spring 13 unwinds and thereby rotates the arbor 12 and the clock-work driving gear 15, the latter will transmit rotary motion to said shift-gear 29, whereby the same is turned on the stationary threaded section 27 of the spindle 26, thus causing said shift-gear to travel outwardly thereon and away from the switch-arm 37, while at the same time rotating the trip-cam 31 to lift said switch-arm 37, against the downward pull of the spring 49, upwardly to remove the portion 48 of said bridging contact means from engagement with the horizontal stationary circuit contact 42. After the contact portions 48 and 42 are thus separated, continued outward movement of the shift-gear 29 permits the thus raised switch-arm 37 to follow under the sidewise pull of the spring 49 until, while in still raised position with its trip-nosing 38 traveling on the rise of the trip-cam 31, the switch-arm carries the contact portion 47 of its bridging contact means again into engagement with the upstanding stationary circuit contact 41; the circuit, however, remaining uninterrupted because the uplifted position of the switch-arm holds the contact portion 48 of its bridging contact means free or still separated from the horizontal stationary circuit contact 42 (see Figures 1 and 2). As the shift-gear completes a revolution, to correspondingly complete a revolution of the trip-cam 31, the cam-nosing 34 of the latter moves beneath and then passes away from the trip-nosing 38 of the switch-arm 37, thus freeing the latter to swing downward, under the downward pull of the spring 49, whereby, while the contact portions 47 and 41 remain engaged under the sidewise pull of the spring 49, the contact portions 48 and 42 are also brought into engagement. Upon this occurrence, the service circuit feeding the winding motor 17 is closed, the current passing through the delivery wire 43 to the stationary contact 41, thence through the portions 47 and 48 of the bridging contact means of the switch-arm to the stationary contact 42, thence by the delivery wire 44 to the motor 17, and thence back to the source through the return wire 45. The operation of the motor 17 through the rotation of its armature shaft 18, drives the worm gear 20, worm wheel 21 and gear 23 to actuate the spring-winding gear 16, whereby the drum 14 is rotated to wind up the clock-spring 13 and thus restore the same to full wound condition. The rotation of the spring-winding gear 16 is transmitted through the pinion 28 to the spindle 26 and its threaded section 27, whereby the latter is turned relative to the shift-gear 29, thus causing the latter to travel inwardly or back from its above-described outwardly shifted position while the clock-spring 13 is being rewound. By the time the clock-spring is fully rewound, the inward movement of the shift-gear 29 will have brought the same into engagement with the switch-arm 37 to again move the same sideways whereby the contact portions 47 and 41 are separated, thus interrupting the circuit feeding the motor and bridging the

spring winding mechanism to a stop, whereupon the above-described operations are repeated.

If at the time the switch-arm 37 is moved to circuit closing position, there should be no current passing through the motor feed circuit, the clock would continue to run and the shift-gear would continue to move outwardly on the threaded section 27 of the spindle 26 under the rotative impulse of the clock-work driving gear 15, and consequently the trip-cam 31 would continue to make a second revolution, until again the passing of its cam-nosing 34 relative to the trip-nosing 38 released the switch-arm for movement to circuit closing position. If at the time of such second closing of the switch-arm, current was available for the motor feed circuit, the spring-winding mechanism would be operated, but owing to the additional outward movement of the shift-gear 29 would continue until the latter retracted its entire distance of outward travel, thus assuring the full rewinding of the spring. If at the time of said second closing of the switch-arm, current was still unavailable for the motor feed circuit, the shift-gear and trip-cam would continue to make successive revolutions, accompanied by continued further outward shifting of the former, until the closing switch-arm functions in connection with a live motor feed circuit, whereupon full rewinding of the clock-spring would immediately take place.

Since in practice the gear ratio of the clock-work driving gear 15 and shift-gear 29 may be so predetermined as to assure a plurality of revolutions of the latter during the total driving or unwinding capacity of the clock-spring 13, it follows that, unless the motor feed circuit remained dead for the entire unwinding time of the clock-spring, some one of the periodic closing operations of the switch-arm would find current available to assure rewinding of said spring before the same ran down completely.

The gear ratio of the spring-winding gear 16 and pinion 28, which rotates the spindle 26 and its threaded section 27, should be the same as the gear ratio of the clock-work driving gear 15 and the shift-gear 29, so that distance of retractive movement of said shift-gear by rotation of said threaded section shall equal any traversed distance of outward travel of said shift-gear on the threaded section 27, all of which will be readily understood.

I have found it advisable, particularly when the novel clock-spring rewinding mechanism is used in connection with home clocks, to provide a means whereby, should service of electric current be discontinued for a considerable length of time, such, for example, as when the home is closed during absence of the family on vacations or under similar

circumstances, the outward travel of the shift-gear 29 will be positively arrested at a point calculated to position the trip-cam 31 in switch-arm releasing position, so that the same occupies and remains in circuit closing relation to the stationary circuit contacts 41 and 42, so that on return of the family and the resumption of current service in the house lines, the clock-spring will be immediately and automatically rewound, either before or after which the clock may be set for correct time indication. This desirable result is obtained in my present invention by providing the stop 50 in connection with the shift-gear 29, so that when the maximum outward movement of the shift-gear 29 is attained said stop 50 will engage with the teeth of the clock-driving gear 15 to positively arrest further rotative movement of both the shift-gear and clock-work after the cam-nosing 34 of the trip-cam 31 has passed the trip-nosing 38 of the switch-arm 37, so that the latter is dropped to circuit closing position, all of which will be readily understood from an inspection of Figures 8 and 9 more especially.

While I have herein shown and described my novel clock-spring rewinding mechanism merely in preferred form and by way of example, it will be obvious that many changes, modifications and adaptations may be made therein and in its mode of application to a clock-work and its spring which will be comprised within the spirit of my invention; consequently I do not limit myself to the exact arrangements and combinations of parts hereinabove described, nor do I confine myself to the exact details of the construction of said parts as shown in the accompanying drawings.

Having thus described my invention, I claim:-

1. In combination with a spring-driven clock-work, a spring winding mechanism including an electric motor and means for opening and closing the motor circuit, said means comprising a circuit control switch device, a spindle having a threaded section, a shift-gear in threaded relation to said threaded spindle section, a switch trip-cam coupled with said shift-gear so as to be rotated thereby on said spindle, said shift-gear being rotated on said threaded spindle section by said spring-driven clock-work to move into inactive relation to said control switch device while subjecting the latter to the control of said trip-cam to produce a circuit closing operation thereof, and said spindle and its threaded section being rotated by said spring winding mechanism to move said shift-gear back into active relation to said control switch device to produce a circuit opening operation thereof.

2. In combination with a spring-driven clock-work, a spring winding mechanism in-

- cluding an electric motor and means for opening and closing the motor circuit, said means comprising a pair of separated stationary contacts in said circuit, an oscillatable switch-arm having contact means to bridge said stationary contacts, spring means to yieldably engage said switch-arm in circuit closing relation to said stationary contacts, a threaded spindle adapted to be rotated by said spring winding mechanism, means on said threaded spindle movable by rotation thereof to produce a circuit interrupting movement of said switch-arm, and said latter means being also adapted to be rotated on said threaded spindle by said spring-driven clock-work to produce a circuit closing movement of said switch-arm.
3. In combination with a spring-driven clock-work, a spring winding mechanism including an electric motor and means for opening and closing the motor circuit, said means comprising a pair of separated stationary contacts in said circuit, an oscillatable switch-arm having contact means to bridge said stationary contacts, spring means to yieldably engage said switch-arm in circuit closing relation to said stationary contacts, a spindle having a threaded section, a shift-gear in threaded relation to said threaded spindle section, a switch-arm trip-cam coupled with said shift-gear so as to be rotated thereby on said spindle, said shift-gear being rotated on said threaded spindle section by said spring-driven clock-work to move into inactive relation to said switch-arm while subjecting the latter to the control of said trip-cam to produce a circuit closing movement thereof, and said spindle and its threaded section being rotated by said spring winding mechanism to move said shift-gear back into active relation to said switch-arm to dispose the same to circuit interrupting position.
4. In a spring actuated clock, a main arbor, a clock-spring, a spring-drum rotatable on said arbor, said clock-spring being connected by one end to said arbor and by its other end to said drum, a clock-work driving gear fixed on said arbor, a clock-spring winding gear connected with said spring-drum, a spring winding mechanism including an electric motor for actuating said clock-spring winding gear, means for opening and closing the motor circuit, said means comprising a motor circuit control switch device, a spindle having a threaded section, a shift-gear in threaded relation to said threaded spindle section, a switch trip-cam coupled with said shift-gear so as to be rotated thereby, said shift-gear meshing with said clock-work driving gear so as to be rotated on said threaded spindle section to move into inactive relation to said switch device while subjecting the latter to the control of
- said trip-cam to produce a circuit closing 65 operation thereof, a driving pinion on said threaded spindle meshing with said clock-spring winding gear whereby said threaded spindle is rotated to move said shift-gear back to active relation to said switch device 70 to produce a circuit opening operation thereof.
5. In a spring actuated clock, a main arbor, a clock-spring, a spring-drum rotatable on said arbor, said clock-spring being 75 connected by one end to said arbor and by its other end to said drum, a clock-work driving gear fixed on said arbor, a clock-spring winding gear connected with said spring-drum, spring winding mechanism 80 including an electric motor for actuating said clock-spring winding gear, means for opening and closing the motor circuit, said means comprising a pair of stationary contacts in said circuit, an oscillatable switch-arm having contact means to bridge said stationary contacts, spring means to yieldably engage said switch-arm in circuit closing 85 relation to said stationary contacts, a spindle having a threaded section, a shift-gear in threaded relation to said threaded spindle section, a switch-arm trip-cam coupled with said shift-gear so as to be rotated thereby on said spindle, said shift-gear meshing with said clock-work driving 90 gear so as to be rotated on said threaded spindle section to move into inactive relation to said switch-arm while subjecting the latter to the control of said trip-cam to produce a circuit closing movement 95 thereof, and a driving pinion on said threaded spindle meshing with said clock-spring winding gear whereby said threaded spindle is rotated to move said shift-gear back to active relation to said switch-arm 100 to produce a circuit interrupting movement 105 thereof.
6. In a clock-spring winding mechanism as set forth in claim 1, a stop-piece connected with said shift-gear cooperating with 110 the spring-driven clock-work to arrest movement of said shift gear when the energy of the clock-spring is substantially expended so as to dispose the trip-cam in switch device releasing position.
7. In a clock-spring winding mechanism as set forth in claim 3, a stop-piece connected with said shift-gear cooperative with the spring-driven clock-work to arrest movement of said shift-gear when the 115 energy of the clock-spring is substantially expended so as to dispose the trip-cam in switch-arm releasing position.
8. In a clock-spring winding mechanism as set forth in claim 4, a stop-piece connected with said shift-gear cooperative with the clock-work driving gear to arrest movement of said shift-gear when the energy of 120
- 125

the clock-spring is substantially expended so as to dispose the trip-cam in switch-device releasing position.

9. In a clock-spring winding mechanism as set forth in claim 5, a stop-piece connected with said shift-gear cooperative with the clock-work driving gear to arrest movement of said shift-gear when the energy of

the clock-spring is substantially expended so as to dispose the trip-cam in switch-arm ¹⁰ releasing position.

In testimony, that I claim the invention set forth above I have hereunto set my hand this 17th day of January 1927.

FREDERICK A. FELDKAMP.
